GLOVE

Conrad F. Sturm, Alexandria, Ind., assignor to
 Glove Corporation, Alexandria, Ind., a corpora-
 tion of Indiana

Application September 14, 1931, Serial No. 562,621

4 Claims. (Cl. 2—161)

My invention relates to improvements in gloves and more particularly to workmen's gloves.

It is one of the objects of my invention to provide a glove which may be readily and cheaply 5 manufactured and which may have a reinforced leather backing across the knuckles.

For the purpose of disclosing my invention I have illustrated one embodiment thereof in the accompanying drawings, in which:

10 Fig. 1 is a rear elevation of a glove embodying my invention;

Fig. 2 is a front elevation thereof;

Fig. 3 is an elevation of the blank for the back of the thumb;

15 Fig. 4 is an elevation of the blank for the back of the little finger;

Fig. 5 is an elevation of the blank for the backs of the middle fingers;

Fig. 6 is an elevation of the blank of the palm 20 including the back of the index finger;

Fig. 7 is an elevation of the blank of the lining for the palm;

Fig. 8 is an elevation of the blank of the lining for the back of the glove; and

25 Fig. 9 is an elevation of the knuckle blank.

In carrying out my invention it will be noted, referring to Fig. 6, that the blank 1 of the palm of the glove is slit along the lines 2, 3 and 4 to provide the fronts of the little finger 5, the two 30 middle fingers 6 and 7 and the index finger 8. That portion of the blank forming the index finger is also cut as at 9 and provided with the curved outer edge 10 which, when the material is folded on the dotted line 11 forms the back 12 of the 35 index finger. This portion of the blank is also given an inward sweeping curve 13. In addition to the above slits the blank is slit on the line 14 to provide the inside portion 15 of the thumb.

An extension 16 is also provided which forms a 40 reinforcement below the line of the gauntlet. The blank 17 for the outside of the thumb is cut as indicated at Fig. 3 and the blank 18 for the back of the little finger is cut as illustrated in Fig. 4 having a narrowed extension 19 at its 45 lower end.

The blank for the backs of the two middle fingers is cut with two diverging portions 20 and 21 and at their centers are cut out to form an opening 22, the walls of this opening forming V 50 shaped notches 23 and 24 in the backs of the respective blanks of the fingers.

As illustrated in Figs. 7 and 8 the liner blanks for the glove are cut, for the palm, as at 25 and for the back as at 26. In assembling the glove 55 the finger portions 20 and 21 are sewed to the fin-

ger portions 6 and 7, with the seams well to the front so that there is no seam directly between the fingers and due to the notched opening 22 and the V shaped cuts 23 and 24, when this blank is stitched into position, it will be noted 60 that a scalloped edge 27 is formed. The thumb blank 17 is stitched to the thumb 15, the blank 15 being turned up and the little finger blank is stitched to the finger portion 5 of the palm of the glove, the stitching in this instance being well 65 toward the front and the extension 19 forming a protection down along the side edge of the glove. The portion 12, as has heretofore been described, is folded and the edge 10 stitched to the free end 70 of the slit 4 forming the index finger with the extension 13 forming a projection down along the side of the glove and into the thumb. A knuckle blank 28 having its upper edge scalloped to coincide with the scallops of the backs of the fingers 75 is stitched between the index finger back and the little finger back and likewise stitched along the scalloped edge. The material between the bottom of this blank and gauntlet 29 may be formed of fabric stitched along the lower edge 80 of the knuckle blank or, if desired, the blank may be extended to the gauntlet cuff to form an all leather glove. The gauntlet 29 may be formed of stiffened cloth material and the glove is preferably lined with the liners 25 and 26, the liner 26 being merely secured in position along its edges 85 and at its bottom edge to the gauntlet and the liner 25 having the tips of its fingers stitched and secured at its bottom edge to the gauntlet.

I claim the following:

1. A glove having V shaped notches in the 90 bottom edges of the backs of the fingers, a back piece secured to said fingers, and a knuckle protecting strip overlying said back piece and secured at its side edges to the side edges of the index and little fingers and having V shaped 95 projections on its top edge stitched to the bottom edges of the backs of the fingers.

2. A glove comprising a palm piece formed with finger-front projections, a finger-back-forming piece provided with a serrated lower edge, said last-mentioned piece being sewn to a plurality of said projections, a knuckle band having a serrated upper edge mating with and sewn to said serrated lower edge, the serrated edge of said knuckle band lapping the serrated edge of 100 said finger-back-forming piece, but terminating short of the crotches between the finger pieces, and a back piece sewn to said knuckle band.

3. A glove comprising a palm piece provided 105 with projections forming fronts for little finger, 110

intermediate finger, and index finger portions, and further provided with portions forming a thumb front piece and an index finger back piece, a separate little finger back piece sewn 5 to said palm piece little finger projection, a piece providing two portions forming backs for said palm piece intermediate finger projections and sewn thereto, said last-mentioned piece presenting, when so sewn, a serrated lower edge, a 10 knuckle band having a serrated upper edge mating with and underlying and sewn to said serrated lower edge and further sewn to said separate little finger piece and to said palm piece index finger back piece, and a back element sewn to 15 said knuckle band to said palm piece.

4. A glove comprising a palm piece provided with projections forming fronts for little finger, intermediate finger, and index finger portions,

and further provided with portions forming a thumb front piece and an index finger back piece, a separate little finger back piece sewn to said palm piece little finger projection, a piece providing two portions forming backs for said palm piece intermediate finger projections and sewn thereto, said last-mentioned piece presenting, when so sewn, a serrated lower edge, a knuckle band having a serrated upper edge mating with and sewn to said serrated lower edge and further sewn to said separate little finger piece and to said palm piece index finger back piece, and a back element sewn to said knuckle band and to said palm piece, the crotches between the finger portions of the completed glove 90 being devoid of seams.
